UNITED STATES PATENT OFFICE.

ALFRED M. PALMER, OF TROY, NEW YORK.

GAME APPARATUS.

Application filed July 23, 1921. Serial No. 486,942.

To all whom it may concern:

Be it known that I, ALFRED M. PALMER, a citizen of the United States, residing at Troy, in the county of Rensselaer and State 5 of New York, have invented new and useful Improvements in Game Apparatus, of which the following is a specification.

Reference may be had to the accompanying drawings, and the reference characters 10 marked thereon, which form a part of this specification. Similar characters refer to similar parts in the several figures therein.

This invention relates to a game in which the object is to project a missile through an 15 aperture in a game-board by means of an elastic connection between the missile and a suitable support.

The principal object of the invention is to afford a better opportunity for the use 20 of skill and accuracy on the part of the operator.

Other objects will appear in connection with the following description.

Fig. 1 of the drawings is a central vertical longitudinal section of my game apparatus taken on the broken line 1—1 in Fig. 2.

Fig. 2 is a cross-section of the same taken on the broken line 2—2 in Fig. 1, showing 30 the game-board in front elevation.

Fig. 3 is a cross-section of the same taken on the broken line 3—3 in Fig. 1, showing the missile-retaining rack in elevation.

Fig. 4 is a top plan view of the missile- 35 retaining rack shown in Fig. 3.

Fig. 5 is a view in rear elevation of a broken-away portion of the game-board.

Referring to the drawings wherein the invention is shown in preferred form, 1 is a 40 game-board provided with one or more apertures, 2, three of such apertures being shown in the drawings.

Each of these apertures is adapted to freely receive a missile, 3, shown in the form 45 of a ball attached to one end of an elastic cord, 4, which cord extends through the corresponding aperture, 2, and is attached at its other end in rear of the game-board, 1, to a stationary cross-bar, 6, at a point, 5, in line with the axis of the aperture, 2.

The cross-bars, 6, are supported by brackets, 7, projecting rearwardly from the game-board, 1, and at a suitable distance in rear 55 of the game-board to permit the missile, 3, when properly directed to be projected through the aperture by the elastic force of

the cord, 4, when said cord is stretched and suddenly released.

At a suitable distance in front of the game-board, 1, I place a missile-retaining 60 rack, 8, formed with slots, 9, to receive the respective elastic cords, 4, whereby the missiles may be retained in readily accessible position for the use of the players.

In playing the game, a player grasps one 65 of the balls, 3, and pulls the same away from the game-board, 1, until the elastic cord, 4, is stretched, and then suddenly releases the ball whereupon the contraction of the elastic cord projects the ball toward the 70 game-board.

If the missile has been properly aimed it will pass through the aperture, 2, through which the connected elastic cord, 4, passes. If not properly aimed it will strike the 75 front of the game-board at one side of the aperture and fail to pass therethrough.

By connecting the fixed end of the elastic cord with a support in rear of the game board at a point in line with the axis of 80 the corresponding aperture it is possible for a player of the game with sufficient skill to in most cases project the missile through the aperture, whereas, a player of lesser skill will have much difficulty in projecting 85 the missile through the aperture.

By providing the board with a plurality of apertures, as shown in Fig. 2, the game may be played by a plurality of players at the same time. 90

It is characteristic of my invention that the inner ends of the elastic cords, 4, are attached to stationary supports, as the bars, 6, at a distance from the board, 1, greater than the diameter of the missile, so that it 95 requires great accuracy to direct the missile through the aperture, 2, in the board.

What I claim as new and desire to secure by Letters Patent is:—

A game apparatus comprising a board 100 provided with an aperture, a missile freely movable through said aperture, a stationary support in rear of said board at a distance therefrom greater than the diameter of the missile, and an elastic connection between 105 said missile and said support at a point substantially in line with the axis of said aperture.

In testimony whereof, I have hereunto set my hand this 20th day of July, 1921. 110

ALFRED M. PALMER.
